DISPATCHING MECHANISM FOR ALARM SIGNAL SYSTEMS

John H. Wheelock, Fitzwilliam, N. H., and Ferdinand F. Humphreys, Caldwell, N. J., assignors to Signal Engineering & Manufacturing Company, New York, N. Y., a corporation of Massachusetts

Application November 30, 1937, Serial No. 177,284

6 Claims. (Cl. 177—360)

The present invention relates to alarm signal systems, particularly fire alarm systems employing a number of bells or other signal devices adapted to be sounded or otherwise operated, in response to the actuation of any one of a number of separate alarm sending stations, such alarm systems being commonly installed in schools, factories, hotels and other large buildings.

In the co-pending application of John H. Wheelock, one of the inventors herein, Serial No. 86,512, filed June 22, 1936, there is shown and described an alarm signal system of the above indicated character, in which the actuation of a sending station is adapted to operate the signals in accordance with the code designation of the selected station. Normally, these signals are operated to give a predetermined number of code sequences, as determined by the construction of the operating mechanism of the station, after which the signals cease to operate, unless the station is again actuated.

There is also disclosed in the aforesaid co-pending application, manually operated means at each station to cause continuous operation of the signals, although not in accordance with a code, after the actuated station has run down. In this way, the actuation of a station will insure not only the transmission of a code to indicate the location of the fire, but also the continued operation of the signals to insure that all persons will be warned that an alarm has been sent.

The object of the present invention is to provide an improved dispatching mechanism for the station of an alarm signal system of the above indicated character, or for any similar system, which mechanism, when once actuated, will automatically cause the operation of the signals of the system on a continuous non-code basis, after the normal functioning of the station has caused operation of the signals through a predetermined number of code sequences. The above and other advantageous features of the invention will hereinafter more fully appear from the following description, with reference to the accompanying drawings, in which:

Fig. 1 is a schematic view, illustrating an alarm system comprising sending stations embodying the invention.

Fig. 2 is a schematic view of a portion of the alarm system of Fig. 1, showing the functioning of the dispatching mechanism to cause operation of the signals on a non-code basis.

Fig. 3 is a view in rear elevation of a dispatching mechanism embodying the invention.

Fig. 4 is a side view of the parts of Fig. 3.

Figs. 5 and 6 are fragmentary views showing details of the mechanism of Fig. 4.

Fig. 7 is a view showing a portion of the parts of Fig. 4, as viewed from the right.

Fig. 8 is a fragmentary sectional view at 8—8 in Fig. 4.

5 Referring first to Fig. 1, an alarm signal system illustrative of the invention comprises the signals 1, which are adapted to be sounded or otherwise electrically operated for giving an alarm are shown, for purposes of illustration, as being of the single-stroke solenoid type, with each providing an operating winding 2 within which moves a magnetic striker 2a. The windings 2 of the signals 1 are adapted to be connected in sections across the supply mains 3 and 4, with balancing resistors 5 between the sections, by means of a number of pairs of relatively movable contacts 6 and 7 forming part of a master controller, generally designated by the reference character 8. The master controller 8 comprises an energizing winding 9 and a magnetic armature 10 carrying the contacts 6 insulated from the armature and movable into engagement with the stationary contacts 7. Therefore, attraction of the armature 10, in response to energization of the winding 9, is adapted to simultaneously energize the signal windings 2, in sections, according to the connection of the several pairs of contacts 6 and 7 to the signal windings 2 and to the supply mains 3 and 4.

30 The winding 9 of the master controller 8 is shown as having one terminal thereof connected to the supply main 3, while the other terminal thereof is connected in series with the thermal element 11 and normally closed contacts 12 and 13 of an automatic circuit interrupter 14 which will be later described. From the interrupter 14, the circuit extends through a number of alarm sending stations 15, and each sending station provides a suitable contacting mechanism, here shown as comprising independent pairs of spaced stationary contacts 16, 17 and 18, 19. In the normal non-operating condition of each station 15, the pairs of contacts 16, 17 and 18, 19 are in engagement. It is to be noted that the contacts 16 and 19 extend beyond the associated contacts 17 and 18, respectively, to provide fingers 16a and 19a terminating in contacts 20 and 21 that are spaced apart. In the operation of a station 15, the fingers 16a and 19a are adapted to be simultaneously flexed from the full to the dotted line position to close the contacts 20 and 21, and to simultaneously disengage contacts 16 and 19 from the stationary contacts 17 and 18, respectively. The showing of the stations 15 is entirely diagrammatic in Fig. 1, and as indicated, the engagement, or disengagement, of the contacts 20 and 21 is under the control of a code wheel 22, adapted to be driven by a suitable clockwork mechanism

upon actuation of the station, as will be herein-after more fully described.

In the non-operating condition of the system shown in Fig. 1, all the contacts 16 and 17 of the several stations 15, are connected in series with the controller winding 9, and the contact 17 of the station farthest removed from the winding 9 in the circuit, is connected by a station conductor 23 to a controlling resistor 24. The resistor 24 is in turn connected in series with the signal windings 2 and balancing resistors 5, and the last signal winding 2 is connected to the farthest station contact 18 through a station conductor 25. The circuit extends through the engaged contacts 18 and 19 of the several stations, and a conductor 26 connects the nearest station contact 19 to the main 4 through a current limiting resistor 27.

Whenever any one of the stations 15 is actuated for the purpose of sending an alarm, rotation of the code wheel 22 causes the first code projection 22a, acting through an operating lever 28, pivoted at 29, to close the contacts 20 and 21 through flexure of the fingers 16a and 19a, while at the same time disengaging contacts 16, 17 and 18, 19, respectively. When this occurs, the contacts 16 and 19 are connected in series at the actuated station through the then engaged contacts 20 and 21, so as to establish a circuit from the supply main 4 through conductor 26, and closed contacts 20 and 21 directly to the controller winding 9, so that the controlling resistor 24, the signal windings 2 and resistors 5 are no longer in circuit with the winding. The resulting increase of current through the armature 10 then pulls up the main armature 10 and causes closure of all the controller contacts 6 and 7.

This increased flow of current through the winding 9 has no immediate effect on the signals 1, which are then out of circuit with the controller winding, but upon closure of the controller contacts 6 and 7, a number of signal energizing circuits are established. Starting from the supply main 4, current flows through a conductor 30 leading to the closed contacts 6 and 7 at the left of the winding 9 and from these contacts 7 signal operating current may then flow through conductor 31a, leading to the signals 1. After traversing the signal windings 2, the operating current then flows through conductor 32 to the closed controller contacts 6 and 7 at the right of the winding 9, and from thence to the grounded supply main 3. This causes the signals to give the first impulse of the code being transmitted by the actuated station 15.

The armature 10 remains up until an operating portion 28a on the lever 28 enters the space between the first and second code wheel projections 22a, thereby turning the lever 28 to an intermediate position, shown in Fig. 5, wherein all the contacts 16, 17, 18, 19, 20 and 21 are open. Opening of contacts 20 and 21 serves to deenergize the controller winding 9, followed by opening of the controller contacts, as the armature 10 drops to restore the signal windings 2 to de-energized condition, but it does not reinsert the resistor 24 in the circuit of winding 9. This cycle of operation is repeated for each projection 22a of the code wheel 22, thereby causing the signals 1 to give spaced code impulses, in accordance with the arrangement of the projections 22a on the code wheel. After the code wheel 22 has made one or more revolutions to transmit the desired number of rounds of signal impulses,

the wheel 22 comes to rest, with the lever 28 in the position of Fig. 1, wherein the station contacts 16, 17 and 18, 19 are again closed, while coding contacts 20 and 21 are open.

In the functioning of the system described thus far, the actuation of a station 15 is adapted to operate the signals through a pre-determined number of code sequences determined by the code designation of the actuated station, after which the signals cease to operate on a code basis, unless a station is again actuated. According to the present invention, each station also provides a dispatching mechanism adapted to continuously operate the signals, although not in accordance with a code, by reclosure of contacts 20 and 21, after the driving mechanism of the station has run down. In this way, the actuation of a station will insure not only the transmission of a code to indicate the location of the fire, but also the continued operation of the signals to insure that all persons will be warned that an alarm has been sent.

As previously pointed out, one terminal of the controller winding 9 is shown as connected to one end of the thermal element 11 of the automatic circuit interrupter 14, which may be of the type shown in Hanel Patent No. 1,863,500, issued July 26, 1932. The interrupter 14 is shown diagrammatically, as providing a pivoted arm contact 12 connected to the other end of the thermal element 11, with the initial tension of element 11 maintaining the contact 12 in engagement with the stationary contact 13. Upon the passage of a predetermined current through the element 11, its heating and expansion permits a spring 12a to turn the arm contact 12 about its pivot to disengage stationary contact 13, whereupon current no longer flows through element 11. The resulting cooling and contraction of the element 11 causes the arm contact 12 to reengage contact 13, whereupon the cycle is repeated to cause the interrupter 14 to make and break the circuit of the element 11 so long as sufficient current flows through the element to cause its expansion. However, during coded operation of the signals, as described above, the successive energizations of the controller winding 9, by full operating current, are not of sufficient duration to have any effect on the thermal element 11, so that the circuit remains closed at the interrupter contacts 12 and 13.

However, upon continued reclosure of the station contacts 20 and 21, after the code wheel 22 has come to rest, to energize controller winding 9 and cause the armature 10 to again pull up, a direct circuit is provided through conductors 30 and 31b for the flow of operating current through the thermal element 11, in series with the winding 9, as indicated by arrows in Fig. 2. When this occurs, expansion of the element 11 permits the spring 12a to turn the arm contact 12, and so open the circuit of the winding 9 at the contact 13. The armature 10 thereupon drops, but is pulled up again when the contact 12 reengages contact 13, upon cooling of the thermal element 11. Therefore, the signals 1 will continue to operate intermittently, although without code sequence, as long as the contacts 20 and 21 remain closed at the actuated station.

Mechanism for non-code operation

Referring now to Figs. 3 and 4, there is shown one form of dispatching mechanism 33 embodying the invention, the mechanism having been removed from the fire alarm box in which it is

normally mounted. A portion of the front of the box is indicated at 34, and when the door of the box has been opened, the mechanism 33 is adapted to be actuated by a hand lever 35, accessible from the front of the box, as shown in Fig. 3. The lever 35 is mounted on a shaft 36, and turning of the lever 35 in the direction of the arrow in Fig. 4, causes a toothed sector 37 to turn a pinion 38 mounted on a shaft 39. This shaft 39 is connected to a spring 40, shown in dotted lines, and turning of the lever 35 causes the spring to be wound. Consequently, upon release of the lever 35, the tension of the wound spring 40 actuates the dispatching mechanism, to cause rotation of a shaft 41, driven from the shaft 39 through suitable gearing 42. Code wheel 22 is mounted on the shaft 41, and the ratio of gearing 42 is such that the code wheel 22 makes several complete revolutions, in response to one actuation of the lever 35, to wind the spring 40 by turning the shaft 39 through a portion of one revolution.

The parts of the dispatching mechanism described thus far are usual in devices of this character, and the invention contemplates the incorporation with the dispatching mechanism of means for automatically causing the alarm signals to operate on a non-code basis, after the mechanism has run down and the signals no longer operate under the control of the code wheel 22.

As best shown in Fig. 4, the spring shaft 39 carries a cam 43, having a notch 44 which is turned through substantially one revolution from the position shown, upon winding of the spring by turning the handle 35. Upon release of the handle 35, the code wheel shaft 41 is driven in the manner previously described, so as to impart a number of complete revolutions to the code wheel 22, and thereby transmit code impulses through movement of the lever 28 which actuates the contacts 16 to 21, inclusive.

The free end of the lever 28 is normally urged in the direction of the code wheel 22 by a spring 45, and a flat surface 46 on the lever 22, adjacent the operating portion 28a, is normally in engagement with a lug 47 of insulating material. The lug 47 is mounted on a lever 48, turnable on the same pivot 29 as the lever 28, and extending between the surface 46 and the contact finger 16a, mounted on an insulating block 49. The several contacts 17, 18 and 19 are also mounted on the block 49 and extend in parallel relation, with all the contacts being connected in the system, as shown in Fig. 1.

As previously pointed out, the contacts 20 and 21 on the fingers 16a and 19a, respectively, are normally out of engagement, but turning of the lever 28 by the rotation of the code wheel 22 is transmitted into movement of the insulating lug 47, so as to engage the contacts 20 and 21 each time a code wheel projection 22a turns the lever 28. Therefore, the resistor 24 is cut out of circuit each time that the contacts 20 and 21 are closed, to cause full energization of the controller winding 9 and the transmission of a code impulse to the signals 1.

In the non-operating condition of the mechanism, the operating portion 28a of the lever 28 is received in a notch 50 of the code wheel 22 that is deeper than the notches between adjacent code projections 22a. In this position of the lever, the surface 46 is far enough withdrawn from the lug 47, so as to maintain engagement between the contacts 16, 17 and 18, 19.

However, as soon as the lever 28 is turned by the first code projection 22a, a cam 51 mounted on the shaft 41 beneath the code wheel 22, see Fig. 5, is turned by a spring 52 to bring a projection 53 into register with the operating portion 28a. A stop arm 54 on the cam 51, bears on the casing 55 of the driving spring 40, to position the projection 53, and it is noted that the surface of the projection 53 is at the same radial distance from the shaft 41 as the bottom of a notch between adjacent code projections 22a. Therefore, when once the lever 28 has been lifted out of the notch 50, the operating portion 28a does not return to the position of Fig. 4 between code projections, but only as far as the surface of the cam projection 53, wherein the contacts 16, 17 and 20, 21, are out of engagement. Thus, the operating portion 28a of the lever 28 does not enter into the notch 50 between successive rounds of the call being transmitted, and the resistor 24 is maintained out of circuit through the transmission of a complete code sequence.

As best shown in Fig. 5, the spring shaft 39 carries a pawl 56 pivotally mounted on a pawl arm 57, that is turnable freely about the shaft 39. A spring 58 acting on the arm 57, see Fig. 3, normally tends to maintain the arm 57 against a stop 59, with the tooth 56a of the pawl bearing on the periphery of the cam 43 adjacent the notch 44. When the driving spring 40 is wound by turning the handle 35 to actuate the mechanism, the cam 43 is turned through substantially one revolution, and as the spring unwinds, the notch 44 approaches the pawl and engages the pawl tooth 56a during that portion of the turning movement of the cam 43 corresponding to the last round of the code. This serves to turn the arm 57 with the pawl, see Fig. 6, and just before the cam 43 comes to rest, an extension 60 of the arm 57 engages a lever 61 mounted on the shaft 41 below the arm 57. The end of this lever 61 provides a notch 62, in which is received a pin 63 provided by the cam 51 on the code wheel shaft. Therefore, just before the spring shaft comes to rest, the engaged pawl 56, acting through the arm 57 and lever 61, turns the cam 51 in a counter-clockwise direction, to move a projection 64 of the cam 51 into engagement with the operating portion 28a of the code transmitting lever 28.

Since the projection 64 provides a surface at the same radial distance from the axis of the shaft 41 as the operating portion of a code projection 22a, the mechanism comes to rest, with the lever 28 occupying the same position that it does when moved by a code projection, thereby closing contacts 20 and 21. Therefore, at the completion of a number of rounds of code signal impulses, when the actuated station has run down, the contacts 20 and 21 remain closed, to short circuit the resistor 24 and cause the controller armature 10 to pull up. The resulting closure of controller contacts 6 and 7 causes the thermal element 11 to operate in the manner previously described with reference to Fig. 1, to bring about intermittent operation of the signals 1 on a non-code basis.

In order to silence the signals and restore the system to a condition of supervision, a lever 65, pivotally mounted at 66, extends in the direction of the pawl 56, with a slot 67 at the end of the lever, receiving a pin 68 mounted on the pawl. The lever 65 provides an arm 69, and as best shown in Fig. 7, an operating portion 70 of

this arm extends at right angles over an arm 71, mounted on a shaft 72 extending through the front 34 of the box. The outer end of the shaft 72 carries a pin 73, and when the door of the box is open, a slotted key carried by a person in authority is inserted to engage the pin 73 and turn the shaft 72 to rock the arm 71.

As best shown in Fig. 8, the end of the arm 71 is normally positioned adjacent to a bevelled surface 70a of the portion 70, so that turning of the shaft 72 by the key, is adapted to rock the lever 65, and thereby lift the pawl 56 out of engagement with the cam notch 44. When this occurs, the spring 58, acting on the cam 43, returns the cam to its original position of Fig. 4, thereby withdrawing the projection 64 from engagement with the code transmitting lever 28, and permitting its operating portion 28a to bottom in the notch 50. This opens contacts 20 and 21 and recloses contacts 16, 17 and 18, 19, thereby restoring the system to a condition of supervision. Obviously upon reaching the box while the mechanism is still operating, a person with the key could immediately lift the pawl 56 by the lever 65 to prevent the contacts 20 and 21 being closed after the box runs down, should the conditions be such as to render unnecessary the sending of continuous non-code signal impulses.

We claim:

1. A dispatching mechanism for an electrical alarm system, comprising relatively movable contacts normally open in the non-operating condition of said mechanism, a spring-driven motor providing a shaft turnable through a predetermined angle when the motor is wound, a coding element operable for a predetermined period, upon unwinding said motor, to move said contacts into and out of engagement to transmit signal impulses in accordance with the code designation of said element, an actuating member freely mounted on said motor shaft, a driving element turnable with the motor shaft to engage said actuating member as said motor unwinds, and means operable by said actuating member to maintain said contacts in closed position after said motor has come to rest.

2. A dispatching mechanism for an electrical alarm system, comprising relatively movable contacts normally open in the non-operating condition of said mechanism, a spring-driven motor providing a shaft turnable through a predetermined angle when the motor is wound, a coding element operable for a predetermined period, upon unwinding said motor, to intermittently move said contacts into and out of engagement to transmit signal impulses in accordance with the code designation of said element, an actuating member freely mounted on said motor shaft, a driving element turnable with the motor shaft to engage said actuating member as said motor unwinds, means operable by said actuating member to maintain said contacts in closed position after said motor has come to rest, and means for manually disconnecting said actuating member from said driving element to restore said contacts to open condition.

3. A dispatching mechanism for an electrical alarm signal system, comprising relatively movable contacts normally open in the non-operating condition of said mechanism, a spring-driven motor providing a shaft turnable through a predetermined angle when the motor is wound,

5 a coding element mounted on a shaft driven from said motor, a movable member actuated by said coding element for intermittently closing and opening said contacts to transmit signal impulses, a cam member mounted on the same shaft as said coding element, normally disengaged from said contact-actuating member, and means actuated from the motor shaft as the motor comes to rest to turn said cam and thereby maintain said contacts in closed position through movement of said contact actuating member.

4. A dispatching mechanism for an electrical alarm signal system, comprising relatively movable contacts normally open in the non-operating condition of said mechanism, a spring-driven motor providing a shaft turnable through a predetermined angle when the motor is wound, a coding element mounted on a shaft driven from said motor, a movable member actuated by said coding element for intermittently closing and opening said contacts to transmit signal impulses, a cam member mounted on the same shaft as said coding element, normally disengaged from said pivoted contact-actuating member, means actuated from the motor shaft as the motor comes to rest for turning said cam to thereby maintain said contacts in closed position, and manually operable means for restoring said cam to its initial position to permit said contacts to open.

5. A dispatching mechanism for an electrical alarm signal system, comprising relatively movable contacts, one pair of which is normally open in the non-operating condition of said mechanism, while other pairs are closed for the flow of supervisory current, a spring-driven motor providing a shaft turnable through a predetermined angle when the motor is wound, a coding element operable for a predetermined period, upon unwinding of said motor to cause the closing and opening of the first-named pair of contacts of the transmission of signal impulses, in accordance with the code designation of said element, while the other contacts are held open, and means operated by turning of said motor shaft for automatically causing said first-named pair of contacts to remain closed after the motor has run down.

6. A dispatching mechanism for an electrical alarm signal system, comprising relatively movable contacts, one pair of which is normally open in the non-operating condition of said mechanism, while other pairs are closed for the flow of supervisory current, a spring-driven motor providing a shaft turnable through a predetermined angle when the motor is wound, a coding element operable for a predetermined period, upon unwinding of said motor to cause the closing and opening of the first-named pair of contacts for the transmission of signal impulses, in accordance with the code designation of said element while the other contacts are held open, means operated by turning of said motor shaft for automatically causing said first-named pair of contacts to remain closed after the motor has run down, and manually operable means for restoring all of said contacts to their normally open or closed positions.
